UNITED STATES PATENT OFFICE.

WILLIAM H. COLLIER, OF NASHVILLE, TENNESSEE.

AUTOMOBILE-STARTER AND ELECTRIC GENERATOR.

1,322,409.

Specification of Letters Patent. Patented Nov. 18, 1919.

Application filed June 9, 1913. Serial No. 772,650.

To all whom it may concern:

Be it known that I, WILLIAM H. COLLIER, a citizen of the United States of America, and a resident of Nashville, in the county 5 of Davidson and State of Tennessee, have invented a certain new and useful Automobile- Starter and Electric Generator, of which the following is a specification.

My invention relates to improvements in starters for internal combustion engines, particularly automobile engine starters, and particularly combined electric starters and electric generators; and my invention comprises an electric starter and generator 15 adapted to be connected to the front end of the crank case of an automobile engine, with the driving shaft of the starting motor in axial line with the crank shaft of the automobile engine. I do not limit myself, however, 20 ever to this particular location of the starting motor or to the connection of the starting motor to the crank shaft of the automobile engine; since obviously the starting motor may be arranged to drive any other 25 suitable shaft of the engine; nor do I limit myself to the use of an electric motor as the starting motor, though I consider the use of an electric motor preferable for many reasons, one of which is that this motor may be 30 used, once the automobile engine is started, as an electric generator. My invention further comprises improved and simplified gearing, whereby, during the starting of the engine, the starting motor transmits its 35 power to the engine through reducing gearing of high gear ratio, and whereby, as soon as such engine commences to operate and reaches a predetermined speed in its operation, the starting motor is driven by the 40 engine at crank shaft speed and becomes an electric generator. My invention further comprises means whereby the starter and generator is protected against injury in the event of back firing of the engine; and 45 means whereby the engine may be turned over by hand when so desired, together with other features all as hereinafter described and particularly pointed out in the appended claims.

50 The objects of my invention are to facilitate the starting of internal combustion engines, particularly automobile engines, motor boat engines, the engines of aeroplanes and dirigible balloons, etc., to avoid 55 occasion for the throwing of gears into and

out of mesh during the starting of such engines; to locate the starting motor, with reference to the engine, in a better position; to convert the starting motor, automatically, and without attention from the operator, into an electric generator immediately the engine begins operation as an internal combustion engine; to provide improved and simplified gearing and other mechanism whereby during the starting of the engine the starting motor operates through reducing gearing of high gear ratio, and whereby as soon as such engine commences operation, as in internal combustion engine, the starting motor is driven by that engine at the speed of the shaft of the engine to which that motor is connected, such motor then becoming an electric generator; to protect such starting motor and generator against injury from back firing or other backward rotation of the engine; to provide for the turning over of the engine by hand, and without the use of the starting motor, when desired; to provide for the efficient protection and lubrication of the gearing; and, in general, to produce a compact, simple and highly efficient combined starting and generating unit.

I will now proceed to describe my invention with reference to the accompanying drawings, and will then point out the novel features in claims. In said drawings:

Figure 1 shows a longitudinal section of a portion of the crank case and associated parts of an automobile engine, and a longitudinal section of a combined starting motor and generator and gearing therefor, constituting one embodiment of my invention.

Fig. 2 shows a transverse section through the gearing on the line $x-x$ of Fig. 1.

Fig. 3 shows a transverse section through the centrifugal clutch mechanism on the line $y-y$ of Fig. 1.

Fig. 4 is a detail view showing side by side, but spaced apart somewhat for clearness of illustration, the internal gear 18, the slotted ratchet wheel 28 and the eccentric 16 having the pin or key 29 adapted to pass through the slot of that ratchet wheel into engagement with ratchet teeth of the gear 18; the gears 18 and 28 being shown in section.

Fig. 5 shows the side view of the slotted ratchet wheel 28.

110

Fig. 6 is a detail section of a portion of the expansion ring 24, showing the means for expanding that ring.

The electric automobile starters now commonly used usually comprise an electric motor upon the armature shaft of which there is a small pinion adapted to be moved into and out of mesh with gear teeth provided on the face of the engine fly-wheel; and this pinion must be moved into mesh with the fly-wheel gear when the engine is to be started, and must be moved out of mesh as soon as the engine has commenced to run. Such location of the starter is disadvantageous for various reasons obvious to those skilled in the art. In some cases the starting motor is combined structurally with the fly-wheel of the engine; a construction which necessarily involves a heavy motor, which is inefficient because of the low speed at which it operates when starting the engine. The engine fly-wheel being in most cases, in automobiles, located at the rear of the engine, in these prior types of starters referred to the starting motor must be correspondingly located. One other form of electric starter now known is mounted at the front of the engine, but with its armature shaft at right angles to the crank shaft of the engine, being arranged to drive the said crank shaft through worm gearing. All of these prior constructions are extremely disadvantageous, for reasons well recognized by machine designers and engineers.

According to the present embodiment of my invention the starting motor becomes in effect a structural part of the engine itself, indistinguishable from the engine itself to the ordinary observer; and this is in practice no small advantage, since the ordinary users dislike devices which are obviously attachments to engines, having the appearance of afterthoughts, and in particular, dislike attachments which require the throwing in and out of gears. In principle my starter is applicable either at the front or at the rear of the engine, and is applicable either to the crank shaft of the engine, or to any other shaft drivingly connected to the crank shaft; but since the space at the rear of the engine proper is, commonly, occupied by a fly-wheel and clutch mechanism, and since the front of the engine is commonly relatively clear, I usually prefer to attach my starter at the front of the engine, with its driving shaft in axial line with the crank shaft of the engine.

In the drawings, 1 designates a portion of the crank casing of an internal combustion engine, preferably the front portion of such casing; 2 designates the crank shaft of the engine. The crank case 1 is provided with a substantially cylindrical integral forward extension 3 within which the starting motor and generator is located. In principle, any

form of motor adapted to communicate rotary motion to a shaft may be employed as the starting motor; but as I prefer to use the starting motor as an electric generator as well, I prefer to employ an electric motor as the starting motor. 4 designates, schematically, the field of such starting motor and generator, and 5 the armature thereof, 6 the commutator thereof, and 7 one of the commutator brushes. I do not limit myself to particular details of construction of the combined starting motor and generator, and hence do not illustrate in detail the construction of such starting motor and generator. The front of the cylindrical extension 3 of the engine crank case is closed by a suitable end cap 8; and the combined starting motor and generator is isolated from the interior of the main portion of the crank case 1 by a partition 9 secured to the front cap 8 by through bolts 10.

11 designates the armature shaft of the starting motor and generator; which shaft passes through a suitable packing box 12 of partition 9 and, at its front end, is supported by ball bearings 13; roller bearings 9a are also provided for this shaft, in partition 9.

The engine crank shaft 2 carries an internal gear 14, shown further in Figs. 2 and 3; upon the hub of which internal gear 14 customarily mount an external gear 15, which forms no portion of the starter and generator, but is used for driving certain mechanism of the engine, not shown. Gear 14 is drivingly connected to crank shaft 2 by means of a pin 16.

The armature shaft 11 is provided at its rear end with a cylindrical extension 16 which is slightly eccentric to the axis of shaft 11, the end of this eccentric 16 fitting within a recess 17 in the end of the crank shaft 2; said recess being concentric with the crank shaft, so that the eccentric bears against the side of this recess at one point only, if at all. Upon the eccentric 16 is mounted an external gear 18 having teeth, as shown particularly in Figs. 2 and 3, adapted to coact with the teeth of the internal gear 14; gear 18 having, however, a less number of teeth than the internal gear 14. In the present instance gear 18 has one less tooth than gear 14, though in principle the gear 18 might have still fewer teeth than the gear 14. Gear 18 is mounted to permit shaft 11 to rotate with respect to it, and for that purpose I have indicated bearing rollers 19 interposed between gear 18 and eccentric 16, a retaining plate 20 being provided for these rollers.

Suitable pawls 21 shown more clearly in Fig. 3, are carried by the gear 18, being provided with pivot pins 22 by which they are pivotally connected to said gear wheel. The partition 9 of the motor casing is provided with a rearwardly projecting flange 180

23 within which is frictionally mounted an expansion ring 24. As shown particularly in Figs. 3 and 6 this expansion ring is a split ring adapted to be expanded by a suitable screw 25 against the inner surface of the flange 23. In general, this ring 24 is stationary with respect to flange 23; but as hereinafter described, said ring 24 may slip with reference to flange 23, in the event 10 of back firing of the engine, or of backward rotation of the crank shaft 2, due to any other cause.

The rear ends 21^a of pawls 21 are adapted to engage suitable recesses 24^a provided 15 in the inner face of ring 24. The front ends 21^b of pawls 21 are extended to form centrifugal weight masses, and these ends are curved, as shown, for compactness of structure, and in order that the centers of 20 gravity of said pawls 21 may be a suitable distance from the axes of the pivot pins 22. A suitable spring 26, passing through holes 27 (Fig. 1) in the ends of the pivot pins 22, tends to resist the action of centrifugal 25 force on the pawls 21 and also acts as a cotter to hold said pawls in place in the gear wheel 18.

Sail pawls 21 are also provided with teeth 21^c adapted to engage teeth of a 30 ratchet wheel 28, when said pawls are moved outward by centrifugal force. This ratchet wheel is also mounted upon the eccentric 16 and is keyed to that eccentric by means of a pin 29. When the pawls 21 35 are in engagement with ratchet wheel 28 the armature shaft 11 is driven by the engine crank shaft 2 at the speed of that crank shaft.

I have not shown the switch mechanism 40 for closing the circuit of the starting motor to a suitable battery to supply current to that motor, and to be charged by that motor when the latter is operating as a generator; but it will be understood that 45 current is supplied to the generator in the ordinary manner.

The operation of the starter is as follows:

The circuit of the motor being closed, the armature 5 starts to rotate, and it may be 50 assumed that this rotation is in the direction indicated by the arrow in Fig. 3; that is to say, in a clockwise direction, as viewed from the front of the machine; thereby the shaft 11 is caused to rotate, and the eccentric 55 16 of that shaft tends to move the gear 18 eccentrically within the gear 14. Gear 18 having a less number of teeth than gear 14, the effect of this attempted eccentric movement of the gear 18 would be to cause 60 said gear to rotate slowly anticlockwise, except that the engagement of the rear ends 21^a of the pawls 21 carried by that gear, with the recesses 24^a of the ring 24, prevents such anticlockwise rotation of gear 65 18. The only other thing that can happen

is forward or clockwise rotation of gear 14 and shaft 21; and this is what occurs; the crank shaft being rotated in a forward direction, very slowly, as compared with the speed of rotation of the starter armature. 70 Such rotation of the crank shaft of the engine should start the engine in operation, and as soon as the engine starts operation, the gear 14 then rotates rapidly forward, carries the gear 18 forward with it; and as 75 soon as this gear 18 reaches a considerable rotative speed, the resulting centrifugal action of the outer weighted ends 21^b of the pawls 21 carries such ends 21^b outward against the action of the spring 26, bringing the teeth 21^c of said pawls into engagement with the ratchet wheel 28, and so driving the armature 5; the starting motor then becoming an electric generator.

It will be seen that the change from operation of the starting motor as a motor to operation as a generator, is entirely automatic; that no shifting of gears is required. When the rotation of the crank shaft of the engine, 2, is stopped, the pawls 21 are moved 90 in again by the spring 26; and if, when the parts stop motion, the rear ends 21^a of pawls 21 should not stop exactly opposite recesses 24^a of ring 24, on the next operation of the motor as a starter, the gear 18 will rotate 95 backward or anticlockwise until the rear ends 21^a of the pawls 21 engage appropriate recesses 24^a, after which the forward rotation of gear 14 and crank shaft 2 will begin. 100

For turning the engine over by hand, when this is desired, I provide the front end of the armature shaft 11 with a pin or key 30 adapted to be engaged by slots in the hub of a suitable starting crank placed over the 105 end of the shaft 11, in the customary manner. Axial pressure on this starting crank then forces the shaft 11 to the left (as viewed in Fig. 1) against the tension of spring 31, until the key 29 engages the 110 ratchet teeth 32 (Fig. 4) on the face of gear 18; the key 29 passing through the slot 33 of gear 28 into engagement with said ratchet teeth. Rotation of such starting crank then rotates the gear 18 directly, causing corresponding rotation of the engine crank shaft. 115

Should the engine back fire, or should the crank shaft 2 start to rotate backward, with considerable force, for any other reason, the thrust of the pawls 21 against the ring 24 120 will cause that ring to move backward within the flange 23. In practice, the screw 25 is set up to such extent that the ring 24 will not move backward during the ordinary starting of the engine, but will slip backward in case any extraordinary thrust is applied to it.

Engines of the sort to which this starter is particularly intended to be applied, viz., automobile and motor boat engines and the 130

like, are commonly provided with closed crank cases, and such closed crank cases commonly contain lubricant which, during the operation of the engine, is splashed about throughout the crank case, lubricating thoroughly all parts therein. By reason of the fact that the gears 14 and 18 are located in this crank case, they will be subject to thorough lubrication. But the starting motor is completely protected by the partition 9 which effectually seals the interior of the crank case extension 3, preventing oil from the crank case from reaching the interior of this extension chamber. The plate 34 covering the recess within which the bearing rollers 9^a are located, and the packing 12, prevent oil from working in material quantity through the bearing of shaft 11 in partition 9 into the motor compartment.

What I claim is:

1. The combination with the engine crank case provided with a chamber adapted to receive a motor, and the engine crank shaft 25 rotatably mounted within said crank case, of a motor within said chamber and having a rotatable member in line with said engine crank shaft, and means for drivingly connecting said shaft and rotatable member 30 comprising gearing, located within said crank case, and connecting said crank shaft and said rotatable motor member, and comprising means permitting said motor to drive said engine crank shaft through said 35 gearing at a high ratio of motor speed to crank shaft speed, and permitting the engine crank shaft to drive the motor through said gearing at a lower speed ratio.

2. The combination with the engine crank case provided with a chamber adapted to receive a motor, and the engine crank shaft 40 rotatably mounted within said crank case, of a motor within said chamber and having a rotatable member in line with said engine crank shaft, means for drivingly connecting said crank shaft and rotatable member, comprising gearing, located within said crank case, and connecting said crank shaft and said rotatable motor member, and comprising 45 means permitting said motor to drive said engine crank shaft through said gearing at a high ratio of motor speed to crank shaft speed, and permitting the engine crank shaft to drive the motor through said 50 gearing at a lower speed ratio; and means isolating said chamber from the main portion of the crank case.

3. The combination with an engine crank case provided, at its end distant from the fly wheel end of said crank case, with a chamber 55 adapted to receive a motor, and an engine crank shaft rotatably mounted within said crank case, of a motor within said chamber and having a rotatable member in line with said engine crank shaft, and means

for drivingly connecting said crank shaft and rotatable motor member.

4. The combination with an engine crank case provided, at its end distant from the fly wheel end of said crank case, with a chamber 60 adapted to receive a combined electric motor and generator, and an engine crank shaft rotatably mounted within said crank case, of a combined electric motor and generator within said chamber and having a 65 rotatable member in line with said engine crank shaft, and means for drivingly connecting said crank shaft and rotatable motor member, comprising gearing located within said crank case, and connecting said crank 70 shaft and said rotatable motor member and comprising means permitting said combined motor and generator to drive said crank shaft, through said gearing, at a high speed 75 ratio of motor to crank shaft, and permitting the crank shaft to drive said rotatable motor member, through said gearing, at a lower speed ratio.

5. The combination with an engine crank case provided, at its end distant from the fly wheel end of said crank case, with a chamber 80 adapted to receive a combined electric motor and generator, and an engine crank shaft rotatably mounted within said crank case, of a combined electric motor and 85 generator within said chamber and having a rotatable member in line with said engine crank shaft, and means for drivingly connecting said crank shaft and rotatable motor member, comprising gearing located within 90 said crank case, and connecting said crank shaft and said rotatable motor member and comprising means permitting said combined motor and generator to drive said crank shaft, through said gearing, at a high speed 95 ratio of motor to crank shaft, and permitting the crank shaft to drive said rotatable motor member, through said gearing, at a lower speed ratio.

6. The combination with an engine crank case provided, at its end distant from the fly wheel end of said crank case, with an integral extension chamber adapted to receive a motor, and an engine crank shaft rotatably mounted within said crank case, of a combined electric motor and generator 100 within said chamber and having a rotatable member in line with said engine crank shaft, and means for drivingly connecting said shaft and rotatable motor member.

7. The combination with an engine crank case provided at its end distant from the fly wheel end of the engine with an integral extension chamber adapted to receive a motor, and an engine crank shaft rotatably 105 mounted within said crank case, of a motor 110

- within said chamber and having a rotatable member in line with said engine shaft, and means for drivingly connecting said shaft and rotatable member.
- 5 8. The combination with an engine crank case provided at its end distant from the fly wheel end of the engine with an integral extension chamber adapted to receive an electric generator, and an engine crank shaft 10 rotatably mounted within said crank case, of an electric generator within said chamber and having a rotatable member in line with said engine shaft, and means for drivingly connecting said shaft and rotatable member.
- 15 9. The combination with an engine crank case provided at its end distant from the fly wheel end of said crank case with an extension chamber adapted to receive a motor, and an engine crank shaft rotatably 20 mounted within said crank case, of a motor within said chamber and having a rotatable driving member, the axis of which is in line with the axis of said crank shaft, and gearing within said crank case connecting said 25 shaft and rotatable member.
10. The combination with an engine crank case provided at its end distant from the fly wheel end of said crank case with an extension chamber adapted to receive a motor, 30 and an engine crank shaft rotatably mounted within said crank case, of a motor within said chamber, a partition isolating said chamber from the main portion of the crank case, said motor having a rotatable 35 member projecting through an aperture in said partition into said main portion of the crank case, the axis of said member being in line with the axis of said crank shaft, and gearing within said crank case connecting 40 said shaft and rotatable member.
11. The combination of two rotatable members, an internal gear carried by one said member and an intermeshing external gear carried by the other said member, one 45 of said members having an eccentric on which the gear carried by said member is mounted, one of said gears having a less number of teeth than the others, and means, controlled by centrifugal force, preventing 50 rotation of the gear mounted on said eccentric when the said eccentric is rotated as a driving member, and locking such gear to the member carrying it when such gear is driven by the other gear.
- 55 12. The combination of two rotatable members, an internal gear carried by one said member, the other said member having an eccentric, an external gear mounted on said eccentric and intermeshing with said 60 internal gear and having a less number of teeth than said internal gear, and means, controlled by centrifugal force, preventing backward rotation of said external gear when said external gear is moved by said 65 eccentric, and locking said external gear to the rotatable member carrying it when said external gear is driven by said internal gear.
13. The combination of two rotatable members, an internal gear carried by one 70 said member and an intermeshing external gear carried by the other said member, one of said members having an eccentric on which the gear carried by said member is mounted, one of said gears having a less 75 number of teeth than the other, a pivoted pawl carried by the gear so mounted on said eccentric, means adapted to be engaged by said pawl to prevent rotation of the corresponding gear when the eccentric is rotated as a driving member, and a ratchet carried by that rotatable member which is provided with the eccentric and pawl, said pawl being arranged to move, under the influence of centrifugal force, into engagement 80 with said ratchet, when the gear carrying such pawl is driven by the other gear.
14. The combination of two rotatable members, an internal gear carried by one said member, and an intermeshing external 90 gear carried by the other said member, one of said members having an eccentric on which the gear carried by said member is mounted, one of said gears having a less 95 number of teeth than the other, two pivoted pawls carried by the gear so mounted on said eccentric, and located opposite one another, means adapted to be engaged by said pawls to prevent rotation of the corresponding gear when the eccentric is rotated as a driving member, and a ratchet carried by that rotatable member which is provided with the eccentric and pawls, said pawls being arranged to move, under the influence of centrifugal force, into engagement 100 with said ratchet, when the gear carrying such pawls is driven by the other gear.
15. The combination of two rotatable members, an internal gear carried by one said member, and an intermeshing external 110 gear carried by the other said member, one of said members having an eccentric on which the gear carried by said member is mounted, one of said gears having a less 115 number of teeth than the other, two pivoted pawls carried by the gear so mounted on said eccentric, and located opposite one another, means adapted to be engaged by said pawls to prevent rotation of the corresponding gear when the eccentric is rotated as a driving member, and a ratchet carried by that rotatable member which is provided with the eccentric and pawls, said pawls being arranged to move, under the influence of centrifugal force, into engagement 120 with said ratchet, when the gear carrying such pawls is driven by the other gear, and spring means tending to resist action of centrifugal force upon said pawls.
16. The combination of two rotatable 125 members, an internal gear carried by one said member, and an intermeshing external gear carried by the other said member, one of said members having an eccentric on which the gear carried by said member is mounted, one of said gears having a less 130 number of teeth than the other, two pivoted pawls carried by the gear so mounted on said eccentric, and located opposite one another, means adapted to be engaged by said pawls to prevent rotation of the corresponding gear when the eccentric is rotated as a driving member, and a ratchet carried by that rotatable member which is provided with the eccentric and pawls, said pawls being arranged to move, under the influence of centrifugal force, into engagement with said ratchet, when the gear carrying such pawls is driven by the other gear.

members, gear mechanism operatively interposed between said members, one of said members provided with two alternative means, other than said other member, for driving it, said gear mechanism comprising means whereby the first named of said members, when driven by one of said alternative driving means, may drive the other said member through such gearing with speed reduction and when driven by the other of said alternative driving means may drive such other member directly.

17. The combination of two rotatable members, gear mechanism operatively interposed between said members, one of said members provided with two alternative means, other than said other member, for driving it, said gear mechanism comprising means whereby the first named of said members, when driven by one of said alternative driving means, may drive the other said member through such gearing with speed reduction and when driven by the other of said alternative driving means may drive such other member through the gearing locked.

18. The combination with an engine shaft rotatably mounted, a support therefor, and a motor in fixed relation to said support and having a rotatable member in line with said engine shaft, said rotatable member provided with an eccentric, intermeshing external and internal gears, one mounted on the engine shaft and the other on said eccentric, a pawl pivoted to the gear so mounted on said eccentric, a member which said pawl is adapted to engage to prevent backward rotation of the gear carrying it, said member adapted to yield in the event of extraordinary backward thrust, and a ratchet carried by the rotatable member of the said motor, said ratchet adapted to be engaged by said pawl, said pawl adapted to move under the influence of centrifugal force into engagement with said ratchet.

19. The combination of an engine shaft rotatably mounted, a support therefor, a motor mounted in fixed relation to said engine shaft and having a rotatable member in line with said shaft and provided with an eccentric, a gear carried by said engine shaft, an external gear rotatably mounted upon said eccentric and meshing with said internal gear, a pivoted pawl carried by said external gear, an adjustable friction member with which said pawl is adapted to engage to prevent backward rotation of its gear, a support for said friction member, said pawl adapted to move outward under the influence of centrifugal force out of engagement with said friction member, and a ratchet carried by the rotatable member of said motor with which said pawl will engage when it moves outward under the influence of centrifugal force.

20. The combination of an engine shaft rotatably mounted, a support for said shaft, a motor mounted in fixed relation to said support, and having a rotatable member in line with said engine shaft, and provided with an eccentric, an internal gear mounted upon said engine shaft, an external gear mounted upon said eccentric, means for preventing backward rotation of said external gear, during driving operation of said motor, and for clutching said external gear to the rotatable member of the motor during driving rotation of the engine shaft, said rotatable member of the motor being movable axially, and provided with a key, said external gear provided with means adapted to be engaged by said key when said motor driving member is moved axially.

21. The combination of an engine shaft rotatably mounted, a support therefor, a motor mounted in fixed relation to said engine shaft and having a rotatable member in line with said engine shaft, and provided with an eccentric, an internal gear carried by the engine shaft, an external gear intermeshing therewith and mounted to rotate on said eccentric and to permit said eccentric to move axially with relation to said external gear, a ratchet wheel also mounted on said eccentric and adapted to permit said eccentric to move axially with respect to it, said eccentric provided with a key, preventing rotation of said ratchet wheel with respect to said eccentric, and said external gear provided with means adapted to be engaged by said key when said eccentric is moved axially, and a pawl pivoted to said external gear and normally out of engagement with said ratchet wheel but arranged to be moved into engagement therewith by centrifugal force, and means adapted to be engaged by said pawl to prevent backward rotation of said external gear.

22. The combination with an engine shaft rotatably mounted, of a motor having a rotatable member in line with said shaft, gearing drivingly connecting said shaft and rotatable motor member and comprising means affording a large speed ratio when the motor member drives the shaft and affording a lower speed ratio when the shaft drives the motor member, said rotatable motor member arranged also for longitudinal motion, and means operated by longitudinal motion of such motor member in one direction, for connecting said motor member to said shaft through said gearing locked.

23. The combination with an engine shaft rotatably mounted, of a motor having a rotatable member in line with said shaft, gearing drivingly connecting said shaft and rotatable motor member and comprising means affording a large speed ratio when

- the motor member drives the shaft and affording a lower speed ratio when the shaft drives the motor member, said rotatable motor member arranged also for longitudinal motion, and means operated by longitudinal motion of such motor member in one direction, for connecting said motor member to said shaft for low speed-ratio drive from the motor member to said shaft.
24. The combination with an engine shaft rotatably mounted, of a motor having a rotatable member in line with said shaft, gearing drivingly connecting said shaft and rotatable motor member and comprising means affording a large speed ratio when the motor member drives the shaft and affording a lower speed ratio when the shaft drives the motor member, said rotatable motor member arranged also for longitudinal motion, and means operated by longitudinal motion of such motor member in one direction, for connecting said motor member to said shaft for direct drive from the motor member to said shaft.
25. The combination of two rotatable members, gear mechanism adapted to drivingly connect said members, one of said members provided with two alternative means for driving it, said gear mechanism comprising means whereby said first named member, when driven by one of said alternative means of drive, may drive the other said member through such gearing with speed reduction through the gearing, said first named member arranged for longitudinal motion and provided with means whereby, when moved longitudinally in one direction, it may drive the other said member directly.
26. The combination of two rotatable members, one of such members arranged also for longitudinal motion, an internal gear carried by one said member, and an intermeshing external gear carried by the other said member, one of said members having an eccentric on which the gear carried by said member is mounted, one of said gears having a less number of teeth than the other, said gear mechanism comprising means whereby one of said members may drive the other said member through such gearing with speed reduction through the gearing, such longitudinally movable member provided with means whereby, when moved longitudinally in one direction, it engages one of said gears directly for direct drive to the other said member through the gearing locked.
27. The combination of two rotatable members, one of such members arranged also for longitudinal motion, an internal gear carried by one said member and an intermeshing external gear carried by the other said member, one of said members hav-
- ing an eccentric on which the gear carried by said member is mounted, one of said gears having a less number of teeth than the other, said gear mechanism comprising means whereby one of said members may drive the other said member through such gearing with speed reduction through the gearing, such longitudinally movable member and one of the parts of the gearing provided, the one with teeth and the other with means adapted to engage such teeth when such longitudinally movable member is moved longitudinally in one direction, whereby the longitudinally movable member may drive the other said member directly through the gearing locked.
28. The combination of two rotatable members, one of which is also longitudinally movable, gear mechanism adapted to drivingly connect said members, and comprising an internal gear carried by one said member and an intermeshing external gear carried by the other said member, one of said members having an eccentric on which the gear carried by said member is mounted, one of said gears having a less number of teeth than the other, a pivoted pawl carried by the gear so mounted on said eccentric, and a ratchet carried by that rotatable member which is provided with the eccentric and pawl, said ratchet having a slot, said longitudinally movable member having a key adapted to pass through such slot of the ratchet when such member is moved longitudinally in one direction, and one of said gears having means arranged to be engaged by such key when the latter is moved longitudinally through the slot of the ratchet.
29. The combination with an engine having a rotatably mounted engine shaft, of a starting motor comprising a rotatably mounted member, gearing functionally interposed between said shaft and rotatable member and adapted to drivingly connect said shaft and member with speed reduction from said member to said shaft, and means thrown into and out of action by longitudinal motion of said rotatable member for connecting said shaft and rotatable member without speed reduction.
30. The combination of a rotatable member, a second member rotatably mounted thereon, a third member also rotatably mounted thereon, means for drivingly connecting said second and third members, said third member having a slot, said first member arranged for longitudinal motion and provided with clutching means adapted to pass through such slot, said second member having means adapted to engage such clutching means when the latter is passed through said slot.
31. The combination of a member mount-

ed both for rotation and slight longitudinal motion, a gear rotatably mounted upon said member, a further member rotatably mounted upon said member, said gear and further member provided, the one with ratchet teeth and the other with a pawl whereby said gear and further member may be connected drivingly, said rotatably and longitudinally movable member and said gear provided with engaging means adapted to be brought into engagement by movement of said longitudinally movable member in one direction.

32. In a motor-generator for use with internal combustion engines, the combination with the engine shaft and an internally toothed gear mounted thereon, an armature shaft mounted concentric with and having a crank-pin extending toward the engine shaft, an externally toothed gear on the crank-pin meshing with the internal gear, an abutment ring having pockets, and pawls mounted on the external gear and adapted to engage in said pockets to prevent said external gear from revolving backward.

33. In a motor-generator for use with internal combustion engines, the combination with the engine shaft, and a motor driven auxiliary shaft shiftable longitudinally upon its axis, means connecting said shafts whereby the first may drive the second at equal speed and the second drive the first at reduced speed, and means whereby the second, when longitudinally shifted, may drive the first at equal speed.

34. In a motor-generator for use with internal combustion engines, the combination of the engine shaft, an armature shaft of an electric generator motor having one end adapted to receive a crank-handle, differential gearing connecting said shafts whereby the engine shaft may drive the armature shaft at equal speed and the armature shaft may drive the engine shaft at equal speed or greatly reduced speed, depending on the relative positions of the shafts.

35. In a motor-generator for use with internal combustion engines, a shaft connected to the engine, an internally toothed gear mounted thereon, an armature shaft mounted concentric with and having a crank pin extending toward the first mentioned shaft, an externally toothed gear rotatably mounted on the crank pin, a fixed member having pockets, a pawl pivotally mounted on the externally toothed gear and having one end adapted to engage in said pockets to prevent the external gear from rotating backward.

36. The combination of a driving shaft and a driven shaft, an internally toothed gear secured to the driven shaft, an externally toothed gear rotatably mounted on the crank-pin, a ratchet wheel also mounted

on the crank-pin, a fixed member having pockets therein, a pawl pivoted on the externally toothed gear and having a portion adapted to be received by the pockets in the fixed member to prevent backward rotation of the externally toothed gear whereby a rotation of the driving shaft causes a rotation of the driven shaft at a reduced speed, means on the pawl for engaging with the teeth on the ratchet wheel when the speed of the driven shaft exceeds a predetermined amount, means for either rotatably connecting the driving shaft directly to the externally toothed gear to drive the latter therefrom or for connecting the driving shaft to the ratchet wheel to be driven therefrom.

37. The combination of a driving shaft and a driven shaft, an internally toothed gear secured to the driven shaft, a crank-pin rigidly connected to the driving shaft, an externally toothed gear rotatably mounted

on the crank-pin, a ratchet wheel also mounted on the crank pin, a fixed member having pockets therein, a pawl pivoted on the externally toothed gear and having a portion adapted to be received by the pockets in the fixed member to prevent backward rotation of the externally toothed gear whereby rotation of the driving shaft causes a rotation of the driven shaft at a reduced speed, means on the pawl for engaging with the teeth on the ratchet wheel when the speed of the driven shaft exceeds a predetermined amount, means for rotatably connecting the driving shaft directly to the externally toothed gear to drive the latter therefrom, means whereby the driving shaft is automatically disconnected from direct connection with the externally toothed gear whenever the speed of the latter exceeds that of the driving shaft.

38. The combination of a driving shaft and a driven shaft, an internally toothed gear secured to the driven shaft, a crank pin rigidly connected to the driving shaft, an externally toothed gear rotatably mounted on the crank-pin, a fixed member having pockets therein, a pawl pivoted on the externally toothed gear and having a portion adapted to be received in the pockets in the fixed member to prevent backward rotation of the externally toothed gear, whereby a rotation of the driving shaft causes a rotation of the driven shaft at a reduced speed, a ratchet wheel mounted on the crank-pin, means on the pawl for engaging with the teeth on the ratchet wheel when the speed of the driven shaft exceeds a predetermined amount, a pin projecting from the driving shaft, said ratchet wheel having formed therein a slot with the edges of which the pin engages when the driving shaft is in one position of adjustment, whereby the driving shaft may be driven from the driven shaft

and at the same speed as the latter, means on the externally toothed gear with which the pin engages to form a direct connection, when the driving shaft is in another position of adjustment whereby the driven shaft may be driven from the driving shaft at the same speed as the latter, and means whereby the driving shaft is automatically thrown out of direct connection with the

driven shaft when the speed of the latter exceeds that of the driven shaft. 10

In testimony whereof I have signed this specification in the presence of two subscribing witnesses.

WILLIAM H. COLLIER.
